J. B. OUELLETTE.
STOP MECHANISM FOR LOOMS.
APPLICATION FILED DEC. 20, 1920.

1,410,831.

Patented Mar. 28, 1922.

Inventor:
John B. Ouellette,
By Cushman, Bryant & Darby
Atty's.

UNITED STATES PATENT OFFICE.

JOHN B. OUELLETTE, OF NEW BEDFORD, MASSACHUSETTS.

STOP MECHANISM FOR LOOMS.

1,410,831.

Specification of Letters Patent. Patented Mar. 28, 1922.

Application filed December 20, 1920. Serial No. 431,948.

To all whom it may concern:

Be it known that I, JOHN B. OUELLETTE, a citizen of the United States, residing at New Bedford, in the county of Bristol and State of Massachusetts, have invented new and useful Improvements in Stop Mechanism for Looms, of which the following is a specification.

This invention relates to an improved stop mechanism for looms and has as its object the provision of certain improved features in a stop mechanism of the type disclosed in my co-pending application, Serial No. 307,591, filed June 30, 1919.

In the application above referred to there is disclosed a stop mechanism comprising a kicker pivotally mounted upon the protector rod of a loom adapted to operate means upon the breast-beam which is connected to the loom shipper-lever. The kicker is normally held in inoperative position, but is moved to position to actuate the shipper-lever operating means when the shuttles are in certain defective and undesirable positions.

The present invention has as one of its objects the provision of an improved kicker device which is provided with a toe adapted to engage the shipper operating means upon the breast-beam, the toe being adjustable toward and from the breast-beam to accommodate the mechanism to looms in which the throw of the lay varies.

Another object of the invention is the provision of improved operating connections between the shipper-lever and the member which is actuated by the kicker. In my co-pending application the mechanism is shown as comprising a bracket secured to the breast-beam, this bracket having located thereon a slideable member which is connected by means of a lever to the shipper. In employing this stop mechanism it has been found desirable to place the bracket which supports the slide in various positions along the breast-beam. In some looms it may be found desirable to locate this bracket immediately adjacent the shipper, while in other looms, due to the proximity of the temple and other parts of the loom, a different position must be selected for the bracket. Hence, it is desirable that the connection between the kicker operated member and the shipper be adjustable in length to adapt the same to any selected position for the bracket supporting this member.

The above and other objects of the invention which are of a more obvious character will become apparent from a reading of the following description and an inspection of 60 the accompanying drawings, in which:

Fig. 1 is an elevational view of the breast-beam of a loom showing my improved mechanism applied thereto.

Fig. 2 is a bottom plan of that portion 65 of the mechanism shown in Fig. 1; and

Fig. 3 is a vertical sectional view taken through the breast-beam and lay of a loom and showing the relation between that portion of the device supported upon the lay 70 and the mechanism shown in Figs. 1 and 2.

Referring to the drawings more in detail, A indicates the lay of a loom and B the breast-beam, the lay being provided with the usual protector rod P which is shown as 75 having thereon for pivotal movement the kicker 6 which has a vertically extending arm 6' and a horizontally extending arm 6''. The kicker is normally movable about the protector rod by means of a spring 10 located between the vertically extending arm 6' and the lay. This movement is prevented by means of the ends 5 of rock shafts, the opposite ends of which are located adjacent the shuttle boxes, except when the shuttle 85 positions are defective.

That portion of my mechanism which is above described is shown more clearly and is claimed in my co-pending application. The kicker shown in the drawings is provided with a toe 9 having a shank portion 9' which is adjustable in the end of the arm 6'' of the kicker, the shank being threaded for this purpose. By adjusting the shank of the toe in the kicker arm, it may be moved 95 toward and from the breast-beam and thus be suitably positioned and adapted to satisfactory cooperation with the particular loom upon which it is positioned and with the remainder of the mechanism supported upon 100 the breast-beam B.

The breast-beam has secured to one face thereof a vertically extending bracket arm 11 as by means of a bolt 12, and this arm at its lower end is provided with a laterally 105 extending portion 11' which terminates in a substantially rectangular plate 13 having at its rear end a lug 14 formed with an opening 15 therein. Supported upon the face of the plate 13 is a slide 16 having an elongated 110 slot 17 therein through which extends a lug 18 upon the plate 13. A cotter pin 19 may

extend through the pin 18 to prevent accidental displacement of the slide 16 from the lug 18. The upper edge of the slide 16 is cut away as at 16' to form a shoulder adapted to be engaged by the kicker toe, and the end of the slide may be formed with a tail piece or guide finger 17' extending through the opening 15. From the lower edge of the slide 16 extends an arm 20 which is formed with an upwardly extending portion 21 paralleling the face of the slide 16, and the upwardly extending portion 21 terminates in a rearwardly and laterally extending arm 22 formed in one edge with a recess or seat 23.

The invention is characterized by the provision of an operating connection which is adjustable in length between the slides 16 and the shipper-lever S of the loom. Such a connection is shown in the drawings and comprises a bell-crank 24 pivotally supported at 25 adjacent the slide so as to be removable and adjustable in position so that it may always be located adjacent the slide. One arm of the bell crank extends into the recess 23 of the slide arm 22, and to its other end is removably connected a link 26 which has a looped end 27 fitting around a pin 28 at the end of the bell-crank. A cotter pin 29 may be passed through the pin 28 to prevent the link from accidentally falling from the bell-crank. The other end of the link is similarly connected to an eye bolt 28 adjustably threaded in an eye 29' of an arm 30 which has a pivotal connection 31 with a bell-crank 32 supported beneath the breast-beam at 33. The other end of the bell-crank 32 engages the dagger 34 pivotally supported in the usual manner upon the breast-beam, and adapted to engage and actuate the shipper-lever when operated through the connection with the slide 16 above described.

From the above description, and from the disclosure in my co-pending application, it will be understood that when there is danger of collision between shuttles upon the race-way by reason of the presence of a shuttle in a box at each end of the race-way, the shafts 5 will be rocked to permit the kicker to pivot about the protector rod P and to bring the toe 9 into engagement with the shoulder 16' of the slide 16 upon the forward or picker motion of the lay. As the lay moves backwardly, the toe of the kicker carries the slide rearwardly or to the left as viewed in Fig. 3, thus swinging the bell-crank 24 about its pivot and through the link connection shown causing movement of the dagger 34 and of the shipper-lever.

In applying the stop mechanism disclosed to a loom, it will be understood that the slide supporting bracket 11 will be placed in any desirable position along the breast-beam, adjustment of the eye bolt 28 permitting va-

riation of the distance between the bell-crank 24 and the bell-crank 32 in conformity with the selected position of the bracket. It will also be understood that should it be found necessary to place the bell-crank 24 at any less or greater distance from the bell-crank 32 than is permitted by merely adjusting the eye bolt, the link 26 will be removed and a longer or shorter link substituted therefor.

It will be understood that this invention is not limited to the specific details of construction constituting the embodiment of my invention shown in the drawings, and hereinbefore described in detail, but many modifications might be made without departing from the scope of the invention which is more particularly defined in the claims.

I claim:

1. In a stop mechanism for looms, a bracket adapted to be supported upon the breast beam, a member supported by said bracket and movable thereon, a kicker adapted to be supported upon the lay and operable to move said member when the shuttles are in defective position, and operating connections adjustable in length between said member and the loom shipper-lever whereby the position of said bracket upon the breast beam may be selectively varied, said connections comprising a plurality of movable members having therebetween a removable connecting link and means for securing the link to one of said members, said last mentioned means being adjustable to accommodate the link to relative movement between said members.

2. In a stop mechanism for looms, a bracket adapted to be supported upon the breast-beam, a member supported by said bracket and movable thereon, a kicker adapted to be supported upon the lay and operable to move said member when the shuttles are in defective position, and operating connections adjustable in length between said member and the loom shipper-lever whereby the position of said bracket upon the breast-beam may be selectively varied, said operating connection comprising a pair of bell-crank levers supported by the breast-beam and means for connecting said bell-cranks whereby the movement of one may be imparted to the other, said connecting means being adjustable in length.

3. In a stop mechanism for looms, a bracket adapted to be supported upon the breast-beam, a member supported by said bracket and movable thereon, a kicker adapted to be supported upon the lay and operable to move said member when the shuttles are in defective position, and operating connections adjustable in length between said member and the loom shipper-lever whereby the position of said bracket upon the breast-beam may be selectively varied, said operating connection comprising a pair

of bell-crank levers supported by the breast-beam, one of said bell-cranks being engaged by said member, and means for connecting said bell-cranks whereby the movement of 5 one may be imparted to the other, said connecting means being adjustable in length, and comprising a removable link adjustably secured to one of said levers.

4. In a stop mechanism for looms, a member 10 movably supported upon the breast-beam, operating connections adjustable in length between said member and the loom shipper-

lever, and means for operating said member, said means comprising a kicker pivotally supported upon the loom protector rod and 15 movable to operate said member when the shuttles are in defective position, and a toe on said kicker adjustable toward and from the breast-beam and adapted to engage said member. 20

In testimony whereof I have hereunto set my hand.

JOHN B. OUELLETTE.
